SPRING STRUCTURE

Desire H. Van Hove, Detroit, Mich., assignor to
 L. A. Young Spring & Wire Corporation, Detroit,
 Mich.

Application December 29, 1932, Serial No. 649,262

2 Claims. (Cl. 155—180)

The main objects of this invention are:

First, to provide an improved spring structure having a border frame of the upholstery clamping type in which the upholstery is very securely clamped in a manner that is not likely to result in cutting the upholstery, and at the same time the clamping means is inconspicuous.

Second, to provide a structure of this character in which the upholstery is very securely retained and at the same time it is not necessary that the parts be formed of heavy material.

Third, to provide a structure having these advantages which greatly facilitates the upholstering operation.

Fourth, to provide a structure which is very strong and rigid, both in the complete structure and during the upholstering operations.

Objects pertaining to details and economies of the invention will definitely appear from the description to follow. The invention is defined in the claims.

A structure which embodies the features of the invention is clearly illustrated in the accompanying drawing, in which:

25 Fig. 1 is a plan view of my improved rim, a portion of the spring supporting bars being indicated in operative relation thereto.

Fig. 2 is a fragmentary vertical section of a spring cushion structure embodying my improvements.

Fig. 3 is an enlarged fragmentary view showing the relation of the rim and the spring supporting bars.

Fig. 4 is a fragmentary perspective view of the rim or border frame.

Fig. 5 is an enlarged fragmentary section through the border frame and upholstery showing the relation of the parts.

The structure illustrated in the accompanying drawing is a cushion adapted for trucks, busses and automobile seats. In this embodiment the body springs 1 of the cushion are mounted upon supporting bars 2 having saddle portions 3 terminating in downwardly facing hook portions 4. The upholstery 5 conventionally shown is provided with a skirt or side portion 6 terminating in a bead 7.

The border frame comprises an outwardly facing channel 8 in which the edge of the upholstery is clamped. The upper arm 9 of this channel is bent downwardly into a flange-like portion 10 which is folded upon itself to provide an upstanding web or flange 11. This portion 9 is preferably inclined inwardly as illustrated. The folded portion presents a rounded

shoulder 12 behind which the bead portion of the upholstery is disposed. The hook portions of the spring supporting bars are engaged over the upper edge of this upstanding web or flange 11.

The lower arm 13 of the channel is clamped upon the upholstery in opposed relation to the rounded shoulder, the edge of the arm 13 lying substantially in the vertical plane of the flange or web 11. The lower edge of the upholstery being wrapped around the shoulder is engaged therewith with a "snubbing" engagement or effect, so that the pull or stress on the upholstery is not resisted entirely by the clamping action of the lower arm or flange 13 of the channel.

With the parts thus arranged a very rigid rim or border frame is provided and one in which the upholstery is securely clamped and retained without any substantial part of the metal being exposed at the outside of the cushion. On account of its great strength and rigidity the structure is well adapted for heavy work such as truck, bus, and car seats and the like. Further, in upholstering the free flange or arm of the channel may be driven down to clamping position, the flange or web 11 and the fold resulting in the clamping shoulder very effectively resisting spring under the blows so that the upholstering operation is greatly facilitated.

I have illustrated and described my improvements in a very practical embodiment thereof. I have not attempted to illustrate or describe certain embodiments or adaptations which I contemplate as it is believed that this disclosure will enable those skilled in the art to embody or adapt the same as may be desired.

Having thus described my invention what I claim as new and desire to secure by Letters Patent is:

1. In a spring cushion structure, the combination with the body springs and supporting bars therefor, of a border frame comprising an outwardly facing upholstery clamping channel, the upper arm of which is downwardly offset and folded upon itself providing an upstanding support with which said spring supporting bars are engaged, said fold presenting a downwardly projecting shoulder partially closing the channel, said channel terminating in a horizontal lower arm, the edge of the lower arm of the channel when closed upon upholstery disposed in said channel being in opposed relation to the said folded downwardly projecting portion, and upholstery having its edge disposed in said channel at the rear of said downwardly projecting portion and clamped

between such portion and the lower arm of the channel.

2. In a cushion structure, a border frame comprising an outwardly facing upholstery clamping channel, the upper arm of which is downwardly offset and folded upon itself providing an up-

standing spring unit support-web or flange, said
